JOHN C. DAVISON, OF FRIENDSVILLE, MARYLAND, ASSIGNOR OF ONE-HALF
TO E. C. W. RYLAND, OF FRIENDSVILLE, MARYLAND.

WRENCH.

SPECIFICATION forming part of Letters Patent No. 703,898, dated July 1, 1902.
Application filed November 21, 1901. Serial No. 83,138. (No model.)

To all whom it may concern:

Be it known that I, JOHN C. DAVISON, a citizen of the United States, residing at Friendsville, in the county of Garrett and State of Maryland, have invented certain new and useful Improvements in Wrenches; and I do declare the following to be a full, clear, and exact description of the invention, such as will enable others skilled in the art to which it applies to make and use the same.

The invention relates to wrenches. The object of the invention is to provide a wrench which shall be simple of construction, durable in use, comparatively inexpensive of production, and one which may be easily and quickly adjusted to fit the work being operated upon.

With these and other objects in view the invention consists of certain novel features of construction, combination, and arrangement of parts, which will be hereinafter more fully described, and particularly pointed out in the appended claim.

In the accompanying drawings, Figure 1 is a side elevation of my improved wrench. Fig. 2 is a longitudinal sectional view through the head of the wrench, the jaws, the worm-wheel, its shaft, and the pinion connected to the worm-wheel. Fig. 3 is a sectional view taken at right angles to Fig. 2, and Fig. 4 is a vertical sectional view through the nut and the swiveled screw.

Referring to the drawings, 1 denotes the handle of the wrench, 2 the head, and 3 the fixed jaw. The handle is formed with an opening 4 and with a cross-piece 5, and the head is formed with a transverse opening 6, intersecting the opening 4, and provided with longitudinal guide-grooves 7 in its side walls.

8 denotes a sliding jaw having an angular shank 9, which is formed with longitudinal supporting guide-ribs 10, which slide in said grooves and support the shank the proper distance from the lower wall of the longitudinal opening in the head of the wrench and also prevent the outward tilting movement of the movable jaw. The lower edge of the shank is formed or provided with worm-teeth 11.

12 denotes a shaft which is secured to the handle and extends across the opening and upon which is journaled a worm-wheel 13, hav-

at its outer end with a head and with a fixed jaw, said head being provided with a longitudinal opening the side walls of which are formed with guide-grooves, of a movable jaw sliding upon said head and having an angular shank to engage the aperture in the head, said shank being provided with ribs to engage said guide-grooves and with worm-teeth on said guide-grooves and with worm-teeth on its lower edge, a shaft, a worm-wheel and

beveled pinion loosely mounted upon said shaft and locked to rotate in unison, a swiveled screw, a beveled gear fixed to said screw

ing connected to turn therewith a beveled pinion 14. The worm-wheel engages the worm-teeth of the shank and may be cast integral with the beveled pinion, but, as shown, 55 is provided with lugs 15, which project between the teeth of the pinion, and thus lock the pinion to turn with the worm-wheel.

16 denotes a fast screw arranged at an angle to the shaft and located in the opening in the handle and having its upper end swiveled in a seat 17, formed in the shaft, and its lower end swiveled in a block 18, screwed to the cross-piece 5 of the handle, whereby said screw may be removed when desired. The 60 upper end of the screw is preferably formed polygonal, as shown at 19, to receive a beveled gear 20, which meshes with the beveled pinion aforesaid and is held to said screw to rotate therewith. 21 denotes a nut mounted 70 to slide upon said screw and by means of which said screw is rotated to rotate its pinion and transmit the movement therefrom to the pinion and worm carried by the shaft. The rotation of the worm moves the movable 75 jaw toward or away from the fixed jaw, according to the direction of movement of the nut, so that I am enabled to obtain a quick adjustment of the wrench to the work being operated upon.

In the drawings I have shown the jaws of the wrench constructed to engage nuts. It is evident that this construction may be modified and the jaws shaped to grasp a pipe or other similar object.

From the foregoing description, taken in connection with the accompanying drawings, the construction, mode of operation, and advantages of my invention will be readily understood without requiring a more extended explanation.

Various changes in the form, proportion, and details of construction may be made within the scope of the invention without departing from the spirit or sacrificing any of the advantages thereof.

Having thus described my invention, what I claim, and desire to secure by Letters Patent, is—

In a wrench of the character described, the 100 combination with the handle provided with an opening and with a cross-piece and formed and engaging the beveled pinion, and a nut mounted upon said screw to rotate the same and thereby slide the movable jaw toward 115 and away from the fixed jaw, substantially as set forth.

In testimony whereof I have hereunto set my hand in presence of two subscribing witnesses.

JOHN C. DAVISON.
